UNITED STATES PATENT OFFICE.

LOUIS W. SCHAAFF, OF HOBOKEN, NEW JERSEY.

WRENCH.

Application filed May 18, 1921. Serial No. 470,645.

To all whom it may concern:

Be it known that I, LOUIS W. SCHAAFF, a citizen of Germany, residing at Hoboken, in the county of Hudson and State of New Jersey, have invented certain new and useful Improvements in Wrenches, of which the following is a specification.

The invention relates to improvements in wrenches. An object of the invention is to provide wrenches having jaws more easily adjusted accurately to the object to be turned, and secured and maintained in effective adjusted position during the turning operation, so that the operator, holding the tool in one hand in position to apply full turning force, may, without materially changing his hold, and with that hand, easily bring about an effective and secure adjustment of the jaws to the object to be turned and the tool can be more quickly, conveniently and effectively used than wrenches heretofore known. This object is attained by providing the wrench with an actuating member mounted upon a part connected with one jaw and having a bearing on a part connected with the other jaw and extending within convenient reach of the hand grasping the handle portion of the tool (so that the operator may, by pressing thereon, move one of the jaws relative to the other jaw) and with suitable means for effectively securing and maintaining the jaws in properly adjusted position. Preferably, such manually-operated means for imparting relative movement to the jaws include mechanism increasing the amount of movement as it is transmitted from the hand to the jaws and operate against the force of a spring arranged to cause movement in the opposite direction, so that the adjustment of the jaws involves a minimum of attention by, and minimum movement of the hand of, the operator, and the means for securing the jaws in adjusted position preferably operate automatically, upon the jaws reaching the point of adjustment to the object, so that disturbance of that adjustment is avoided, as illustrated in a preferred form hereinafter described. Other objects appear in connection with the description hereinunder.

Wrenches differ according to the use for which each is designed, and the present invention is applicable to many different kinds of wrenches and susceptible of various differing embodiments in each kind, to meet

the particular use and circumstances. The accompanying drawings, accordingly, show an illustrative embodiment of the preferred form as follows:

Fig. 1 is a view of one side of a wrench embodying the principles of the invention partly in section on the line 1—1 of Fig. 5; Fig. 2 shows a section thereof on the line 2—2 of Fig. 4, with the jaws of the wrench in tightly closed position; Fig. 3 is a similar view, with the jaws in open position; Fig. 4 is a section on the line 4—4 of Fig. 1; Fig. 5 is a section on the line 5—5 of Fig. 1; Fig. 6 is a detailed sectional view of the securing mechanism; Fig. 7 is a detailed view of the preferred form of actuating member; Fig. 8 is a view of a modified and novel jaw construction preferred for certain uses; Fig. 9 is a view thereof in position adjusted to a nut; Fig. 10 is a vertical view thereof; and Fig. 11 illustrates another form of jaws adapted particularly to turning a pipe or similar object.

For clarity of description and explanation, the wrench of the invention may be considered as divided into a part connected with each of the jaws, the means for moving one part relative to the other to secure the adjustment of the jaws to the object to be turned, and the means for securing and maintaining the parts in adjusted position. While the movement is relative, it is convenient to differentiate the jaws as fixed and movable. The invention contemplates that either the outer jaw or the inner jaw may be the movable jaw, but a form wherein the outer jaw is movable has been selected for illustration, because it is thought to give somewhat better effect to additional and valuable, but not always essential, features hereinafter described.

The part connected with the fixed jaw 1 consists of a shaft having one portion adapted to co-act with the movable-jaw part, to maintain alignment between the two parts, and another portion adapted to serve as a handle or portion for the application of the turning power. In the form shown in the drawings, the provision for maintaining alignment between the two parts consists of a longitudinal hole with parallel sides, 2, formed in the shaft and adapted to receive and contact with a portion, 3, of the movable-jaw part of corresponding cross-section extending into the hole, 2, for a dis-

tance at least sufficient to maintain alignment. A lower portion of the fixed-jaw shaft is provided with a space, 4, connected with the hole, 2, and adapted to contain 5 the moving and locking mechanism.

In Figs. 1, 2 and 3, an additional feature, referred to above, is illustrated as consisting of dividing the shaft into two parts so as to obtain relative movement between 10 them in such manner that the force applied to the handle portion of the shaft to turn the object is made to exert a more effective grip of the jaws upon the object to be turned. In the form shown, one part of the shaft 15 is provided with an aperture, 5, adapted to receive pins, 6, fixed to the other part of the shaft, and so shaped that either of said pins may move longitudinally a sufficient distance therein, while a side of the 20 aperture, 7, affords a bearing for a spring, 8, bearing against said pins and keeping the parts in alignment except when the turning power is applied. When the shaft 25 is thus divided into two parts, with proper double-acting hinge construction between them, and proper provision made for locking the movable-jaw part of the wrench to the handle portion of the fixed-jaw part, as hereinafter described, the power applied 30 in turning in either direction exerts sufficient lever power (having one of the pins, 6, as a fulcrum) to cause the jaws to move towards each other and thus exert a more effective grip upon the object to be turned. 35 For many uses, this additional feature is unnecessary and the shaft is a rigid piece not divided into two parts. But for many other uses, as, for instance, in the case of the pipe wrench, the jaws of which are illustrated in Fig. 11, and where the form of 40 adjusting and locking mechanism operates less accurately than the preferred form, so that slippage therein requires compensation, or considerations of cost are comparatively 45 unimportant, the addition of this feature is preferred.

The movable-jaw part of the wrench consists of a shaft comprising a portion, 3, co-acting with a portion of the fixed-jaw part 50 to preserve alignment, and a portion, 9, adapted to be engaged by the locking mechanism. When the shaft of the fixed-jaw part is articulated so as to embody the additional feature above described, the shaft 55 of the movable-jaw part is preferably provided with a portion which is both flexible enough to adapt the shaft to the movement of the hinge construction and stiff enough to transmit the push of the moving mechanism on the lock-engaging portion, 9, to 60 the jaw portion, 3, as well as strong enough to stand the strains exerted by the turning movement. A portion of chain, 10, comprising several flat pieces of metal pivoted 65 together, has been found to comply with

the requirements. It will be understood that when the invention is embodied in forms not embracing the hinge construction of the fixed-jaw part, the movable-jaw part may consist of a single piece of metal. 70

The means for moving the movable-jaw part relative to the fixed-jaw part to adjust the jaws to the object to be turned comprise a member having a bearing or fulcrum on the fixed-jaw part and extending with 75 in convenient reach of the hand holding the tool by the handle portion, the movement of which, as by a finger of that hand, is transmitted by suitable, and preferably multiplying, mechanism to the movable-jaw 80 part. To minimize the amount of attention required from the operator in effecting the adjustment of the jaws and make the tool automatically effect as much as possible of the operation, in the preferred form pressure on the actuating member is made to 85 operate against the force of springs in such manner that when the pressure is released the tool itself completes the adjustment and the maintenance thereof during the turning 90 operation. In the form shown in the drawings, the member 11, considered as an actuating member, is in substance a lever mounted or fulcrumed on the pin, 12, fixed to the fixed-jaw part and extending 95 within easy reach of the hand grasping the handle portion of the tool, so that, for instance, the forefinger may be used conveniently to exert pressure at 13. The transmission of this movement to the movable 100 jaw, in the form shown, is through the extension or arm, 14, to the short arm of the shifter, 15, pivoted at 16, the longer arm of the shifter being provided with a pin, 17, which operates in an oblongated aperture, 105 18, provided in the shaft of the movable-jaw part. While other forms of transmitting the movement by lever or gear systems may be used, the particular form shown is preferred because it combines the 110 advantages of few parts and little space with multiplication of distance and accuracy of direction. A comparatively strong spring, 19, between the fixed-jaw part and the movable-jaw part is arranged 115 to exert its force against the pressure on the actuating member, preferably in line with the longitudinal movement of the movable-jaw part.

The means for locking the parts in ad- 120 justed position against undesirable relative movement during the turning operation comprise a surface on a portion of the mov- 125 able-jaw part adapted to be engaged by a corresponding surface fastened to the fixed-jaw part, with suitable mechanism to move such surfaces into or out of engagement, preferably automatically upon the adjust- 130 ment of the jaws on the object to be turned and without manual movement which might

disturb the adjustment. In the form shown in the drawings, a portion of the shaft, 9, is made round and the surface thereof threaded, provided with ridges or otherwise roughened; members 11 and 20 are fastened to the fixed-jaw part by being pivoted on the pins 12 and 21; the surfaces of said members 11 and 20, contacting with the shaft, 9, when said members are turned on their mountings, 10 are shaped and threaded, ridged or roughened to correspond with and engage the surface of the shaft, 9, this shaping of said members preferably including making the line of the contacting surface with due regard to the location of the pivot, so that the surfaces will be completely freed from, or in sufficient engagement with, the shaft, 9. In the form shown, the member 11 is part of the actuating member, this particular construction affording the additional advantage of making one piece serve both purposes; and that piece is preferably further provided with the means for moving the member 20 out of engagement with the shaft and locking it into engagement therewith. These means for moving the member 20 out of engagement take the form of a lug, 22, placed so as to strike a portion of the member 20 shaped to contact with said lug and therebelow cut away to permit further movement of the actuating member, 11, without too much movement of the member 20. The means shown for locking the member in engagement take the form of a lug, 23, placed 35 to contact with a portion of the member 20, the contact side of the lug, 23, preferably corresponding with an arc of the pivot, 12, and the contacting portion of the member 20 being preferably somewhat at an angle to the lug, so that the force of contact tends to force the lug upward and prevent slipping. As indicated by the dotted line, the portion of the member 20, on which the lug, 23, bears, is so shaped that after the lug has 40 been withdrawn from contacting position, the member 20 may pass over it, and the member 20 thus be given sufficient movement to free it from engagement with shaft 9. A spring or springs, 24, are arranged to exert 45 pressure against the members 11 and 20, tending to force them into engagement with the shaft, 9, bearings for said spring or springs being conveniently provided on portions of said members opposite to the portions carrying or contacting with the lugs. The force exerted by said spring or springs is insufficient to effect engagement against the force exerted by the spring 19, but sufficient to effect engagement when the force 50 so exerted is diminished, so that when the jaws of the wrench have been separated by pressure on the actuating member, the spring 19 operates to draw them together until they contact with and adjust themselves to the object to be turned, whereupon 55 the force of the spring or springs, 24, moves the contacting surfaces of the members 11 and 20 into engagement with the co-acting surface of the shaft 9, so that the jaws are locked against separation. The use of a 60 spring or springs, such as 24, to effect the operation of the means for securing the jaws against separation, is preferred to the use of manually-operating means which are available, because the movement of the hand involved in operating the latter is apt to disturb somewhat the adjustment of the jaws to the object to be turned. It is also preferred to arrange the mountings of the locking mechanism on the fixed-jaw part of the tool in such fashion that the bearings of the locking mechanism on that part are disposed angularly with respect to the bearings of such mechanism on the movable-jaw part, so that force exerted in the direction of separating the jaws tends to tighten the engagement between the contacting surfaces. Thus 65 in the form shown, the greater the force exerted in the direction of moving the shaft, 9, upwardly, the more tightly the contacting surfaces of the shaft, 9, and members 11 and 20 are forced into effective engagement. For that reason, such an arrangement is to be preferred to an arrangement wherein the engaging members simply move in contact 70 horizontally, or other arrangements which are available.

The jaws of the wrench of the invention will vary according to the particular uses. In Figs. 1, 2 and 3 is illustrated the usual type of jaws common to monkey wrenches. In Fig. 11 is shown a type of jaws adapted to wrenches to be used in holding or turning pipes or like objects. In Figs. 8, 9 and 10 is shown a novel type of jaw preferred 75 when the invention is to be embodied in a certain type of automobile wrench. The jaws there shown comprise a plurality of members, 25, mounted in the jaws in such manner that they may turn so that one side thereof contacts fully with a side of the nut to be turned, whereby such jaws are suited to engage effectively nuts of different sizes. Such members may be conveniently held by pivots, 26, and provided with 80 springs, 27, acting to maintain them normally in position best suited to introducing the nut between the jaws. Jaws provided with such members present the further advantage that when they have been adjusted to a nut by the relative movement of the jaws and turning power is applied to the tool, the members exert an additional clinching or gripping action upon the nut 85 to be turned, of particular value when, by reason of wear or otherwise, it is difficult to turn it. When such jaws are employed in a wrench having also the hinge feature hereinabove disclosed, a tool of remarkable gripping capacity is provided. If the 90

120

125

130

adjustment and locking means of the invention are embodied in forms less accurate than the the preferred form hereinabove described, these means of increasing the effectiveness of the gripping of the jaws are desirable to compensate for any inaccuracy in the adjustment.

It will be understood that in elaborating herein the preferred form and sundry details thereof, there is no implication that the invention is not susceptible of advantageous use in other forms. By reason of considerations of cost and work to be performed, sundry features of the preferred form may

15 be advantageously omitted and the invention embodied in different forms, in many cases. The parts, improvements and combinations claimed as the invention are pointed out in the following claims, to wit:—

20 1. A wrench comprising jaws one of which is movable relative to the other, shafts connected with the jaws and having portions co-acting to maintain alignment therebetween, manually-actuated means for imparting relative longitudinal movement to one shaft in one direction, said shaft being so movable to the full extent of its range of movement, spring-actuated means for imparting movement thereto in the other direction, and spring-actuated means operable upon adjustment of the jaws to the object to be turned to lock the jaws against separation.

25 2. A wrench comprising jaws one of which is movable relative to the other, shafts connected with the jaws and having portions co-acting to maintain alignment therebetween, manually-actuated means for imparting relative longitudinal movement to one shaft in one direction, said shaft being so movable to the full extent of its range of movement, spring-actuated means for imparting movement thereto in the other direction, and means operable upon adjustment of the jaws to the object to be turned to lock the jaws against separation.

30 3. In a wrench having jaws one of which is movable relative to the other, a lever to effect relative movement between the jaws to open the jaws to substantially their full extent fulcrumed on a part connected with one jaw and having a bearing on a part connected with the other jaw and an arm within convenient reach of the hand grasping the handle portion of the tool to actuate the lever.

35 4. In a wrench having jaws one of which is movable relative to the other, a member for actuating relative movement between the jaws to open them mounted on a part connected with one jaw and extending within convenient reach of the hand grasping the handle portion of the tool, in combination with means for transmitting the movement of the actuating member to the other jaw

and increasing the amount of movement in the transmission.

5. In a wrench having jaws one of which is movable relative to the other, an actuating member mounted upon a part connected with one jaw and extending within convenient reach of the hand grasping the handle portion of the tool, in combination with means for transmitting its movement to effect relative movement of the jaws when it is moved in one direction, and means for securing the jaws against separation when moved in the other direction.

6. In a wrench having jaws one of which is movable relative to the other, a lever for moving one of the jaws in one direction to open the jaws to substantially their full extent, and a spring for moving the jaw in the opposite direction to close the jaws upon the object to be turned, said lever being fulcrumed on a part connected with one jaw and bearing on a part connected with the other jaw and extending within convenient reach of the hand grasping the handle portion of the wrench.

7. In a wrench having jaws one of which is movable relative to the other, actuating means for moving one jaw in one direction to open the jaws to substantially their full extent, and a spring for moving the jaw in the opposite direction to close the jaws upon the object to be turned, said actuating means having provision for locking the jaws against separation during the turning movement and comprising a member movably mounted upon a connection of one jaw and adapted to be moved on its mounting to engage a connection of the other jaw, in combination with means for making and breaking said engagement.

8. In a wrench having jaws one of which is movable relative to the other, mechanism for locking the jaws against separation during the turning operation comprising a member movably mounted upon a connection of one jaw and adapted to be moved on its mounting to engage a connection of the other jaw, in combination with spring-actuated means for making, and manually-actuated means for breaking, said engagement, said member being arranged to move the second jaw in one direction to open the jaws to substantially their full extent, and a spring adapted to move said jaw in the opposite direction to close the jaws upon the object to be turned.

9. In a wrench comprising relatively movable jaws, one of said jaws having a shank provided with a rough surface, actuating means for moving one of the jaws in one direction to open the jaws to substantially their full extent and for securing the jaws against separation during the turning operation, said actuating means comprising a member connected with one

jaw and having a portion adapted to engage the rough surface of the other jaw shank, and means for moving the movable jaw in the opposite direction to close the 5 jaws upon the object.

10. In a wrench comprising relatively movable jaws, one of said jaws comprising a shaft having a roughened portion, means for moving one of said jaws in one direction to open the jaws to substantially their full extent and locking the jaws against separation during the turning movement, said means comprising a member having a portion adapted to co-act with the roughened portion, and means for moving the movable jaw in the opposite direction to close the jaws upon the object and for effecting engagement between said portions.

11. In a wrench, a jaw having a shaft 20 divided into two portions connected together by bearings fixed on one portion and entering an aperture in the other por-

tion so shaped as to permit suitable longitudinal movement of either bearing therein, in combination with a connection with the 25 other jaw passing between said bearings, and means for locking said connection to the portion of the first named shaft below said bearings.

12. In a wrench, a shaft connected with 30 one jaw, comprising two parts joined together by a double-acting hinge, in combination with a shaft connected with the other jaw, and means for locking it to the portion of the first named shaft below said 35 hinge.

13. In a wrench, jaws each of which comprises a plurality of members turnably mounted therein and having edges shaped to conform to a surface of the object to 40 be turned, and springs adapted to maintain the contacting surfaces of said members normally separated from each other.

LOUIS W. SCHAAFF.
